UNITED STATES PATENT OFFICE.

EDWIN A. WEBSTER, OF GROVELAND, MASSACHUSETTS, ASSIGNOR TO CHARLES K. FOX, OF HAVERHILL, MASSACHUSETTS; IDA L. FOX, LAMONT H. CHICK, AND ROBERT D. TRASK, EXECUTORS OF SAID CHARLES K. FOX, DECEASED.

LEVELING-MACHINE.

1,086,100.

Specification of Letters Patent.

Patented Feb. 3, 1914.

Application filed June 10, 1909, Serial No. 501,238. Renewed December 6, 1913. Serial No. 805,185.

To all whom it may concern:

Be it known that I, EDWIN A. WEBSTER, of Groveland, county of Essex, State of Massachusetts, have invented an Improvement in Leveling-Machines, of which the following is a specification.

This invention relates to certain improvements in leveling machines of the type shown in the U. S. patent to Webster No. 10 727,516, dated May 5th, 1903.

In leveling shoes with a leveling roll, such as is shown in said patent, it is customary to move the jack back and forth beneath the roll, tipping the shoe by means of the supporting mechanism of the jack, first to one side and then the other, so that there is a strong downward pressure on the edges of the shoe, which tends to cant the last on the heel-post and split it. Furthermore, 20 when a last becomes weakened by splitting, while it might still be used for other purposes, it cannot be practically used in a leveling machine unless suitably supported. While a leveling roll, such as is shown in 25 said patent, is especially desirable for use in leveling turned shoes, there are several particularly serious objections to such use, which may be explained as follows:—In the 30 operation of these machines the leveling roll is rotated so that its engaging surface moves toward the toe of the shoe while in engagement with the sole thereof. The friction between the roll and sole causes a strong 35 tendency to draw the sole forward on the last, with the result that the back portion of the counter is sometimes drawn onto the bottom of the last, or the heel of the sole is lifted from the bottom of the last, so that 40 this portion of the shoe must be drawn back into position by hand. It is, moreover, not practical to level the heel-seat of a shoe in the machine of said patent, for the reason 45 that the operator is liable to move the jack so far toward the rear that the ribs of the roll catch on the back end of the sole and pull the shoe partly or wholly from the last, with probable damage thereto. It is, therefore, necessary to "beat out" the heel-seat 50 by hand when the forepart is leveled in the machine. The drawing action of the roll also tends to stretch the sole so that it is longer than the last, and the toe of the sole projects beyond the toe end of the last. These results are highly objectionable, as it

is practically impossible to get the shoe 55 back into proper shape, when it has been pulled out of shape, and, at the best, it necessitates the employment of labor to remedy the defects.

An object of my invention is to counteract effectively the drawing action of the leveling roll on the sole, so that the counter will not only be prevented from being pulled out of position or onto the bottom of the last, but that said portion will also be 65 drawn onto the last more smoothly and tightly by the leveling operation, than it was before said operation was performed, so that the sole will be firmly held against the bottom of the last throughout its entire 70 surface and the heel-seat will be made square with the counter-portion of the shoe.

A further object of the invention is to provide means whereby the entire surface of the heel-seat may be leveled by the roll, 75 and all possibility of the roll being brought into engagement with the end of the sole is prevented.

Another object of my invention is to counteract the tendency of the roll to stretch the 80 sole, so that it will be made longer than the last.

I accomplish these objects by the means shown in the accompanying drawing, in which—

Figure 1 is a side elevation of a jack made according to my invention, the position thereof on a leveling machine being indicated, and the parts being shown in unlocked position. Fig. 2 is a similar view of 90 the jack on a larger scale, showing the parts in locked position. Fig. 3 is a front end elevation of the jack. Fig. 4 is a section on the line 4—4 of Fig. 2, showing a rear end elevation of the jack. Fig. 5 is a central 95 section on the line 5—5 of Fig. 4. Figs. 6 and 7 are detail sectional and plan views showing the position of the last holding parts after the leveling operation has been finished. Fig. 8 is a sectional view at the 100 line 8—8 of Fig. 5. Fig. 9 is a section at the line 9—9 of Fig. 7.

As shown in the drawing, *a* indicates the main frame of a leveling machine, having the leveling roll *b*, and the *U*-shaped support *c* for the jack, mounted to swing transversely in the *U*-shaped frame *c'*, the latter being so mounted that it may be moved

and tilted forwardly and rearwardly, and moved vertically, so that the last supported on the jack may be universally moved, as described in said patent.

- 5 According to my invention a pair of upright plates or ears d , d' are rigidly mounted on, and preferably cast integral with the yoke c , and a heel-post support e , made in the form of a flat plate and bearing the
 10 usual heel post e' on the upper end thereof, is pivoted on a pin f between said plates d , d' to swing in the customary manner. Said heel post support is provided with an arm e^2 which extends obliquely upward from the
 15 rear side thereof, and a lever g is mounted to swing on a pivot h , held in the end of said arm, said lever g being provided with a longitudinal slot g' , to receive said arm e^2 , said slot extending from a point adjacent
 20 the upper end of said lever to a point adjacent its lower end. The lower end of said lever g , below said slot, is provided with a cam face g^2 , which extends obliquely across the same, and the support e is provided with
 25 a cam face e^3 , which is disposed opposite said face g^2 and extends convergently upward with relation thereto. The upper end of said lever g is provided with a hollow post g^3 which extends longitudinally thereof, at a slight angle thereto, and a heel
 30 holder i is slidably mounted on said post, said holder having a chamber i' , in which the post is located. A spring j is arranged in the bore of said post g^3 and is interposed
 35 between the bottom of said bore and the bottom of the chamber i' , the reciprocating movement of said holder on said post being limited by means of a stop screw g^4 , mounted in post g^3 and extending into a slot i^2
 40 formed in the holder, said screw being readily removable to permit the holder to be removed from the post. Said holder i is provided with a U-shaped or concave recess formed between two rearwardly ex-
 45 tending projections i^3 , i^4 , and the inner surface of said recess has a lining k secured thereto, said lining preferably being of slightly corrugated rubber, or some other material which will not injure the upper of
 50 a shoe, when forced into engagement therewith, but which is, however, adapted to engage the same frictionally with considerable force. The inner walls of said projections
 55 i^3 , i^4 , diverge at their ends sufficiently to permit the heel portion of a shoe to enter the same readily, while the inner portion of the recess is formed to fit closely about the heel end of the shoe, so that the lining k may be pressed firmly against the sides of
 60 the heel or counter-portion of the shoe. The inner sides of said walls extend nearly vertical at their lower portion and their upper portions are inclined inwardly to a slight extent, as shown in Figs. 6 and 9, to
 65 conform to the shape of the heel portion

of the shoe adjacent the sole. The upper surface i^5 of the holder is slightly rounded, said surface corresponding somewhat to the longitudinal curve of the roll b , a surface of considerable width being provided between 70 the bottom of the recess and the outer sides of the holder. Holders of different sizes are provided, but each holder is adapted for a large number of sizes.

A set lever m is pivotally mounted on a 75 shaft n , said shaft being held in an ear d^2 of the upright d , and said lever being extended obliquely downwardly and inwardly to the central vertical plane of the jack, as shown in Fig. 3. The lower end of said lever is pivotally connected to one end of a horizontally extending link o , and the opposite end of said link is pivoted to one arm p of a bell crank lever, said arm extending upwardly at approximately right angles to 80 link o and the other arm p' of said lever extending approximately horizontally forward. The intermediate portion of said lever is mounted on and secured to a pivot q , which is rotatably mounted in an ear e^4 on 85 the rear edge of the heel post support e , adjacent the lower end thereof. The shaft q extends through the ear e^4 and an arm p^2 is secured to the projecting end thereof, in a position parallel to the arm p' , said arms 90 p' , p^2 being thereby held closely adjacent the opposite sides of the support e , and acting as one arm. The front ends of said arms p' , p^2 are each provided with longitudinal slots p^3 and a roll r is provided, having projecting trunnions r' , which extend into said slots p^3 , said roll being thereby permitted to rotate therein and to move longitudinally of said arms p' , p^2 . When thus held in the 95 ends of arms p' , p^2 , said roll r is supported 100 between the cam faces g^2 and e^3 , in position to engage both, or either of said faces, as 105 hereafter described.

The particular locking mechanism for the lever m is of well-known form, and comprises an angular hand lever s , pivoted at s' on lever m , and a link t pivoted to an intermediate portion of said lever and to a crank arm u , the latter being secured on a shaft u' rotatably mounted in lever m adjacent its 110 lower end, said shaft having a pawl v thereon adapted to engage teeth v' mounted on upright d . A spring w on lever m acts 115 normally to hold said pawl in engagement with said teeth v' . The lever mechanism above described does not differ materially either in construction or operation from the ordinary set lever.

A toe rest x is pivotally mounted at x' on the frame c and is adjustably connected by 120 a swivel screw y to the rear edges of the uprights d , d' , as in said prior patent. The upper end of the rest is provided with an abutment z , which is mounted on a stem z' to move vertically in the toe rest, a spring 125 130

z^2 being provided to support the same, and a stop screw being also provided to limit the upward movement thereof by said spring. The abutment z is provided with a V-shaped recess z^4 in its front side, formed to receive the toe end of a shoe, and its rear side is provided with a rearwardly extending projection z^5 , so that a slightly rounded, but nearly flat surface is provided which extends rearwardly for some distance from the bottom of said recess.

The manner in which the above described device operates may be described as follows: The toe rest is adjusted by means of the screw y in the proper relation to the heel post for the size of shoe which is to be leveled, and the last, bearing the shoe to be leveled, is then placed in position on the jack in the ordinary manner, the parts being in the position of Fig. 1. The lever m is then pushed rearwardly or downwardly until the last is jacked, as shown in Fig. 2, and as hereinafter described, said lever being automatically locked in the position to which it may be advanced by its pawl and ratchet mechanism. The manner in which the last is jacked may be described as follows:—As the upper end of the lever m is pushed rearwardly the lower end thereof draws the link o toward the front. As the link o is connected to the arm p of the bell crank lever, and the latter is pivoted on the lower end of the heel post support e , by means of shaft q , which is located at some distance below its pivot f , the preliminary movement of lever m causes the support e and lever g to be swung about pivot f as a center until the tip of the shoe is carried into engagement with the toe rest, so that resistance to further movement of the heel post toward the toe rest is encountered. Further movement of the lever m then causes the arms p' , p^2 to be swung upwardly, forcing the roll r upwardly between the converging cam faces e^3 and g^2 . The cam face e^3 is arranged to extend obliquely outward with relation to an arc having the axis of shaft q as a center, so that, as the arms p' , p^2 are swung upwardly, said roll r will be pushed away from said axis, said movement being permitted by the slotted bearings provided therefor in said arms p' , p^2 . The cam face g^2 , however, is arranged to extend obliquely inward with relation to said axis, and moreover, as said roll r is pushed away from said center, it will be forced against said face g^2 , so that, as the arms p' , p^2 are swung upwardly, the lower end of lever g will be swung forwardly and the holder i , carried thereby, will be swung rearwardly toward the heel post e' , until said holder is forced against the heel end of the shoe. Resistance to the upward movement of the arms p' , p^2 , thus encountered, causes the forward pull on link o to be exerted on the shaft q , so that the

heel post e' will be forced rearwardly to an extent sufficient to press the toe of the shoe or last firmly down on the toe rest. Simultaneously with this movement the holder i will be pressed still more forcibly against the heel of the shoe, so that, when the hand lever m is pushed down or rearward as far as possible, the last will be firmly jacked on the heel post and toe rest and the holder i will at the same time be firmly pressed against the heel of the last, the parts being locked in this position. It may be observed that, while there is, under some conditions, a certain sequence of operation, both the jacking and clamping operations are performed practically simultaneously when the hand-lever m is pushed rearwardly, and the reaction caused by the resistance encountered in performing one operation will cause the other to be also performed. However, the sequence of operation, while largely dependent on conditions of size and adjustment, is, in fact, a matter of no consequence, the desired result being that both operations shall be performed with one lever, in practically one operation.

The heel-holder i and abutment z are so arranged that, when the last is jacked, the toe of the shoe will bear firmly against the bottom of recess z^4 in said abutment and said holder and abutment will both extend for a short distance, (approximately one half an inch in practice,) above the surface of the sole, as shown in Fig. 5.

The last having been jacked, the leveling operation is performed as follows: The jack is raised and moved rearward until the middle portion of the heel-seat is directly beneath the axis of the leveling roll b and then the jack is raised, so that the roll bears against the projections i^3 , i^4 , of the holder, and the movement is continued until the holder has been pressed down, so that its upper face is on a level with the surface of the sole and the roll may bear against the same with sufficient force to perform the leveling operation thereon. The jack is then moved forwardly and rearwardly until the heel-seat is properly leveled and the sole pressed firmly against the heel of the last. In performing this operation the projections i^3 , i^4 , act as positive guides for the operator, causing the shoe to be held exactly vertically with relation to the roll, so that equal pressure will be brought to bear on each side of the heel-seat and all possibility that the heel-seat will be pressed out of position with relation to the counter is prevented. This is a matter of much importance, for, in beating-out the heel-seat by hand, it frequently happens that the heel-seat is not left in the desired shape, so that the heel, when attached, does not set properly with relation to the counter portion of the shoe. Inasmuch as the holder fits closely about the edge

of the sole at the heel end, and a broad surface is provided in the rear of the shoe at the level of the sole, after the holder has been pressed down by the roll, as above described, 5 it is impossible for the roll to be brought into engagement with the rear edge of the sole at any time, permitting the heel of the sole to be leveled to the extreme heel end without danger of injury to the shoe, for if 10 the jack is pushed back so far that the roll bears on the surface of the holder in the rear of the shoe, the holder cannot be further depressed except with great difficulty, so that the holder thereby acts to prevent the 15 jack from being raised so that the sole is at any time above the level of the under side of the roll.

While the holder *i* is being depressed, as above described, it is, at the same time, being held in firm frictional engagement with the back or counter portion of the shoe, so that, as the holder is depressed, it will cause the whole counter portion to be pushed or drawn down onto the last as far as possible. 25 The result is that the sole is drawn down firmly onto the heel of the last and all wrinkles in the counter portion are pulled out, an operation, which has previously been performed by hand with not little difficulty, 30 being performed as an incident to the leveling operation in a length of time which is inappreciable and in a much more effective manner than when performed by hand.

After the heel-seat has been leveled, the 35 rest of the sole will be leveled in the usual manner, the holder *i* firmly supporting the last against sidewise tipping. Moreover, the holder *i* acts to clamp the counter portion of the upper firmly against the last 40 about its entire end, so that the upper cannot be pulled onto the last bottom by the drawing action of the roll upon the sole. This action is also, to a certain extent, resisted by the abutment *z*, which bears against the toe 45 end of the sole and prevents the sole from being drawn out so that it is longer than the last.

As above stated, the abutment *z* extends above the level of the sole, so that when the 50 toe portion of the sole is leveled the roll will be caused to engage said abutment and press the same down to the level of the sole, to permit the leveling operation to be performed on this portion of the sole. In either 55 position, however, it bears against the front edge of the sole, but, by having it normally extend above the level of the sole, an effective abutting face will be presented under all conditions. The abutment *z* also acts 60 as a guard for the tip of the shoe, preventing possible injury thereto by the roll.

The tension of the springs, which lift the holder and abutment *z* is only sufficient to lift said parts when the last is removed, 65 neither having sufficient strength to lift

said parts when the last is clamped in position.

I do not desire to limit my invention to the particular form of heel holder *i* shown and described, as any form of engaging means, device or devices, which will perform the functions thereof, is within the spirit and scope of my invention, the most important of said functions being to draw down the counter portion of the shoe onto the last or jack, to clamp said counter portion against the last, so as to hold the same against the drawing action of the leveling devices, or leveling roll, to act as a guard to prevent the leveling roll from pulling the 80 shoe from the last or causing injury thereto by engaging the end of the sole thereof, to act as a guide to the operator to prevent unequal pressure at opposite sides of the heel-seat, and to support the last effectively 85 during the leveling operation. Moreover, while the particular form of means and devices shown and described, for accomplishing the operations of jacking the last and clamping the heel-portion of the shoe practically simultaneously, or in practically one operation, is more desirable than any form of which I am aware, yet I do not desire to limit my invention to the particular form 90 of operating device or hand lever disclosed, or to the particular actuating means which are interposed between the operating lever and the jacking and clamping devices, as any means whereby the jacking and clamping operations may be performed as one 100 operation, or by practically one motion of the operator, as by moving a handle, I consider to be within the spirit and scope of my invention.

The particular form of actuating means 105 shown for the clamping and jacking devices, I consider to be especially desirable, as they are simple and durable and unlikely to get out of order, and, moreover, are adapted to adjust themselves automatically to widely 110 varying conditions.

Having thus described my invention, what I claim as new and desire to secure by Letters Patent is:—

1. In a sole-leveling machine, leveling devices comprising a last support, a sole-engaging device and means for relatively moving the same to level the sole of a shoe held on said support, a counter-engaging device and means for pressing the same against 115 the back of a last held on said support frictionally to engage the counter portion of a shoe held thereby, and means disposed to be engaged by said leveling devices, as they are moved into operative relation, to move 120 said engaging device vertically with relation to the sole to draw the counter portion of a shoe onto the last in advance of the leveling operation, substantially as described.

2. In a sole-leveling machine, leveling de- 130

- 5 vices comprising a last support, a sole-engaging device and means for relatively moving the same to level the sole of a shoe held on said support, an engaging-device having a face of relatively soft material disposed frictionally to engage the counter portion of a shoe held on a last carried by said support and means disposed to be engaged by said leveling devices, as they are moved 5 into operative relation, to move said engaging device vertically with relation to the sole to draw the counter portion of the shoe onto the last in advance of the leveling operation, substantially as described.
- 10 15 3. In combination with the leveling devices of a leveling machine, a last support, a clamping device for pressing the counter portion of a shoe against a last held on said support, and means, actuated by said leveling devices as they are moved into operative relation, for moving said clamping device to draw said counter portion onto the last in advance of the leveling operation, substantially as described.
- 15 20 25 4. In combination with a leveling device of a leveling machine, a last jack for supporting a shoe in inverted position, an engaging device having a support for holding the same in engagement with the counter portion of a shoe held on a last supported by the jack, with a portion thereof in position to be engaged by said leveling device, and means permitting said engaging device to be pressed downwardly by said leveling device, while held in engagement with said counter portion to draw the latter onto the last in advance of the leveling operation, substantially as described.
- 25 30 35 5. In a leveling machine, a jack for supporting a last in inverted position, and a leveling device, a holder having means for pressing the same in engagement with the counter portion of a shoe held on the last, with a portion thereof projecting above the level of the sole in position to be engaged by said leveling device, and means permitting said holder to be depressed by said leveling device while held against said counter-portion, as the sole and leveling de-
- vice are moved together to draw the counter-portion onto the last in advance of the leveling-operation, substantially as described. 50
6. A leveling machine having in combination a jack for supporting a last in inverted position and a leveling roll disposed transversely with relation thereto, a holder adapted to engage opposite sides of the counter portion of a shoe held on the last and having the opposite portions thereof disposed to be engaged by the opposite end portions of the roll as the roll performs its leveling operation, substantially as described. 55
7. A leveling machine having in combination a jack for supporting a last in inverted position and a leveling roll disposed transversely with relation thereto, a depressible holder adapted to engage opposite sides of the counter portion of a shoe held on the last, means for supporting said holder with the engaging portions thereof above the level of the sole of a shoe on the last to permit the same to be engaged by the roll and depressed thereby as the sole of the shoe and the roll are brought into operative relation, substantially as described. 60
8. A leveling machine having in combination a leveling roll and a universally movable jack for holding a last transversely thereof, a holder having side portions disposed to engage opposite sides of the counter portion of a shoe held on the last, said side portions having engaging faces at their upper edges disposed to be engaged by the opposite end portions of the roll to cause the jack to be held in predetermined relation to the roll, and means permitting said holder to yield to permit the leveling operation to be performed while engaged by said side portions, substantially as described. 65
- 70 75 80 85 90
- In testimony whereof, I have signed my name to this specification, in the presence of two subscribing witnesses.
